CLAIM

We claim the ornamental design for a panel for a gazebo, as shown and described.

DESCRIPTION

FIG. 1 is a front perspective view of the panel for gazebo of this design;

FIG. 2 is a rear perspective view of the design of FIG. 1; FIG. 3 is a front perspective view of a second embodiment of a panel for a gazebo, the rear being substantially the same; The panel for a gazebo has been broken away to indicate indeterminate length.

1 Claim, 3 Drawing Sheets

FIG. 1

FIG. 2

FIG. 3

UNITED STATES PATENT AND TRADEMARK OFFICE
CERTIFICATE OF CORRECTION

PATENT NO. : Des. 402,376
INVENTOR(S) : Nicole St. Gelais, et. al.
DATED : December 8, 1998

It is certified that error appears in the above-identified patent and that said Letters Patent is hereby corrected as shown below:
